UNITED STATES PATENT OFFICE.

THOMAS F. FEENY, OF BOULDER, COLORADO.

FENCE-WIRE FASTENING.

SPECIFICATION forming part of Letters Patent No. 621,491, dated March 21, 1899.

Application filed November 12, 1898. Serial No. 696,251. (No model.)

To all whom it may concern:

Be it known that I, THOMAS F. FEENY, a citizen of the United States, residing at Boulder, in the county of Boulder and State of Colorado, have invented certain new and useful Improvements in Fence-Wire Fastenings; and I do hereby declare that the following is a full, clear, and exact description of the same, reference being had to the annexed drawings, making a part of this specification, and to the letters of reference marked thereon.

The present invention has for its object to provide a simple and effective means for securing barbed or other fence wires in position; and it consists in the details of construction substantially as shown in the drawings and hereinafter described and claimed.

Figure 1 of the drawings is a perspective view showing my improved means of securing the fence-wire to the stay rod or wire; Fig. 2, a side elevation showing the fence-wire and the clamping plate or clip in section; Fig. 3, a detail view in perspective of the clamping plate or clip.

In the accompanying drawings, A represents the usual stay rod or wire of a fence, to which the usual fence-wires B are secured. The means employed for securing the fence-wires in place, as shown in Fig. 1, consists of a U-shaped metal clamping plate or clip C, which plate or clip has a rectangular opening a through its upper extension b, and its lower extension c is forked, as shown at d. A flat-sided wedge D engages the rectangular opening a and passes down through the forked end c, as shown in Figs. 1 and 2 of the drawings. The clamping plate or clip C being concave or rounding upon its inner side and rear end, as shown at e, serves to tightly clamp the wires B when drawn against them

by the wedge D much more effectively than were the inner surface of the plate or clip perfectly straight or flat sided, as the pressure against the wires is at an angle and toward a given center, as illustrated by the dotted cross-lines shown in Fig. 2 of the drawings. The lower extension c of the plate or clip C being forked, as shown, and not having an opening closed at its end, as in the upper extension b, the necessity of a specially-constructed wedge of certain width is not required, as the forked end c enables the lower end of the wedge to project beyond the forked end in a lateral direction if necessary to drive the wedge a sufficient distance down to securely clamp the wires. This feature of the invention is considered of material importance in providing more effective means for firmly and rigidly securing the fence-wires in place by the use of a wedge not especially adapted to the clamping plate or clip.

Having now fully described my invention, what I claim as new, and desire to secure by Letters Patent, is—

The means herein described for securing fence-wires in place, consisting of a U-shaped clamping plate or clip having a rectangular opening through its upper extension and its lower extension having a forked end as shown, and a tapering wedge to engage the clamping plate or clip, said wedge engaging the plate or clip in a vertical direction, substantially as and for the purpose set forth.

In testimony that I claim the above I have hereunto subscribed my name in the presence of two witnesses.

THOMAS F. FEENY.
